UNITED STATES PATENT OFFICE

152,814

DESIGN FOR A BOX OR THE LIKE

Henry P. McGovern, Fayville, Mass., assignor to Dennison Manufacturing Company, Framingham,
Mass., a corporation of Massachusetts

Application March 28, 1947, Serial No. 138,016

Term of patent 3½ years

(Cl. D53—13)

To all whom it may concern:

Be it known that I, Henry P. McGovern, a citizen of the United States of America, residing at Fayville, county of Worcester, and Commonwealth of Massachusetts, have invented a new, original, and ornamental Design for Box or the like, of which the following is a specification, reference being had to the accompanying drawing, forming a part thereof.

Fig. 1 is a top plan view of a box embodying my new design;

Fig. 2 is a rear elevational view thereof;

Fig. 3 is a side elevational view thereof; and

Fig. 4 is a view similar to Fig. 3 with the cover of the box in opened position.

I claim:

The ornamental design for a box or the like, substantially as shown.

HENRY P. McGOVERN.
